(57) CLAIM

The ornamental design for a wine storage apparatus, as shown and described.

DESCRIPTION

FIG. 1 is a perspective view of a first embodiment of a wine storage apparatus showing my new design;

FIG. 2 is a top plan view thereof, the bottom plan view being identical thereto;

FIG. 3 is a right side elevation view thereof, the left side elevation view being identical thereto;

FIG. 4 is a front elevation view thereof, the rear elevation view being identical thereto;

FIG. 5 is a perspective view of a second embodiment of a wine storage apparatus showing my new design;

FIG. 6 is a top plan view thereof, the bottom plan view being identical thereto;

FIG. 7 is a right side elevation view thereof, the left side elevation view being identical thereto;

FIG. 8 is a front elevation view thereof, the rear elevation view being identical thereto;

FIG. 9 is a perspective view of a third embodiment of a wine storage apparatus showing my new design;

FIG. 10 is a top plan view thereof, the bottom plan view being identical thereto;

FIG. 11 is a right side elevation view thereof, the left side elevation view being identical thereto; and,

FIG. 12 is a front elevation view thereof, the rear elevation view being identical thereto.

The broken lines depict unclaimed environmental subject matter and form no part of the claimed design.
